UNITED STATES PATENT OFFICE

GEORGE CORNUELLE, OF CINCINNATI, OHIO

BRICKLAYER'S SCAFFOLDING

Application filed September 30, 1927. Serial No. 223,188.

My invention relates to provision of suitable scaffolding for use by brick-layers in erecting walls, which fully satisfies requirements for rapid and accurate work, with the elimination of many tiresome movements, and confusion of materials which is the result of the use of scaffolds at the present time.

In laying brick in a wall, it is always advantageous for the layer to see over the top 10 of the work he is doing, so that he can line the wall both inside and outside. In the usual practice of laying, the brick-layer has his brick, tile and the like dumped on the floor and builds his wall up to around five 15 or six feet. He then calls for a scaffold on which the hod-carriers dump the brick, mortar, tiles and the like, and he mounts the scaffold and works up to the ceiling of a room, from the scaffold, again reaching above 20 his chest with brick, if the wall is of normal height, and the scaffold not too high for the hod-carrier to dump his brick thereon.

The hod-carrier, in having to dump the brick on the top of the scaffold, stands on the 25 floor and has to spill out the materials in the hod onto the scaffold, thus making a scattered pile, mingling brick and tile; and making it part of the bricklayer's work to separate his materials, while laying them.

According to my invention, a scaffold is provided in which there are two stages or 30 runs on which the brick-layer can work, preferably so arranged that the board on which the brick-layer stands is shifted up as the wall gets higher, and supports at a high level 35 may be swung into place to support it, without delay in working time. When the wall has reached waist high, the brick-layer calls for the scaffold, and has the materials 40 dumped on top of it, and standing on an intermediate run, lays the wall up to the top of the scaffold, at all times seeing over the wall to the outside thereof. He then mounts to 45 the top of the scaffold and continues his work with his materials at hand.

By the use of my novel scaffold, the number of bricks per day which are laid by the usual brick-layer, are increased very materially 50 without apparent effort on the brick-layer's part, which is a great saving, and fur-

themore, the outside of the wall can always be readily observed as the work proceeds.

I accomplish my objects by that certain construction and arrangement of parts to be hereinafter more specifically pointed out and 55 claimed.

In the drawings:—

Figure 1 is a plan view of a scaffolding showing the mortar board supports in retracted position.

Figure 2 is a detail perspective view showing the preferred type of mounting for the mortar board supports.

Figure 3 is a side elevation showing one of the scaffolding units.

I have shown a scaffolding in which there are two assemblies of upright supports or frames which are supported with lateral braces, but it will be within the scope of my invention to provide more than two uprights 73 if desired.

The scaffolding is formed of two frames composed of substantially spaced vertical pieces 1 which are secured together with diagonal braces 2 nailed or screwed thereto. A permanent run board support is indicated at 3 on which run boards 4 extending across between the horses are usually disposed for the brick-layer to stand on. The run board support is formed by extensions of the horizontal braces 5 which are nailed to the uprights. Extending across between the vertical supports 1 secure, as with nails, the cross braces 6. On the cross braces or on the upper part of the frame I have provided iron bands 7 in 80 which the top sliding supports 8 are mounted. The provision of the top sliding supports for either a series of mortar boards or run boards such as are indicated at 10 constitutes the essence of my invention, and the particular scaffolding structure which has been described may be otherwise varied.

The scaffolding shown is particularly adapted to normal wall construction. It will allow a brick-layer to build a wall of nine or more feet without requiring any additional scaffolding other than what has been described.

In laying a wall, the brick-layer starts to lay bricks on the ground level while he is 10

standing on the ground, and the hod-carrier places the bricks and mortar for the first three feet of the wall near the brick-layer. When the wall has been built up to about the three foot level, the brick-layer has the scaffolding brought up and he places it several feet from the wall with the run boards 4 on the side of the scaffold nearest the wall. He then has the hod-carrier place his bricks and mortar on boards such as are indicated at 10. The wall is then laid up to about the six foot level. After the wall has reached this level, the brick-layer pulls out the sliding supports 8 and has boards placed across between the extended supports. He can then continue to have bricks and mortar disposed on the top of the scaffold, and by stooping he can build the wall on up to nine feet or higher.

Thus, with the simple scaffolding which I have planned, a brick-layer may be very materially assisted, and the speed of the work will be found to greatly increase. It will be usual for the run boards to be temporarily disposed on the supports, although they may be permanently fastened thereto.

Having thus described my invention, what I claim as new and desire to secure by Letters Patent, is:—

A brick-layer's scaffold comprising upright members, with bracing extending between the upright members so as to provide a rigid structure, a pair of run board supports extending beyond the vertical plane of the upright members substantially at the three foot level, and a pair of slidingly mounted supports at the top of the scaffold substantially at the six foot level which, when extended, will support a temporary run board.
